UNITED STATES PATENT OFFICE.

BENJAMIN F. MIKESELL AND HARRY F. GILLIAM, OF KANSAS CITY, MISSOURI.

AUTOMATIC PHOTOPRINTING AND NUMBERING DEVICE.

Application filed April 4, 1921. Serial No. 453,179.

To all whom it may concern:

Be it known that we, BENJAMIN F. MIKESELL and HARRY F. GILLIAM, citizens of the United States, and residents of Kansas City, county of Jackson, State of Missouri, have invented a certain new and useful Improvement 5 in Automatic Photoprinting and Numbering Devices, of which the following is a complete specification.

The present invention relates to photo printing apparatus, and aims to provide a novel and improved numbering mechanism of a character designed to be embodied as a part of the photo printing apparatus and 10 operated simultaneously with the photo printing operation for marking a number upon each of the prints as the same are produced.

One particular object in view is to provide 20 a combined photo printing and numbering apparatus of the character specified, in which the numbering device is so constructed as to mark the number substantially centrally upon each photo print during the photo printing operation.

For carrying out this construction, we have devised a cover member movably mounted in relation to the photo printing surface, and provided with a numbering device 30 associated centrally with reference to said cover member and operating in conjunction therewith to mark the number upon the print during each photo printing operation. For this purpose the said cover member is provided with a central opening for 35 the mounting of the numbering device, which latter is mounted for a slight degree of relative movement to permit the use of a yielding actuating connection between the cover and numbering device, and also for allowing the cover member to be tilted into an 40 inclined position relatively to both the printing surface and said numbering device while the latter is still in operative position.

In this connection one of the special objects in view is to provide a cover member 45 movable into and out of operative relation to its printing surface and having a yielding actuating means adapted to permit movement of said cover member away from the printing surface into an inclined position with reference to said surface.

With the foregoing general objects in view, the invention will now be described by 50 reference to the accompanying drawings, illustrating one form of construction which

we have devised for embodying the proposed improvements, after which the novel features therein will be particularly set forth and claimed.

60 In the drawings—

Figure 1 is a side elevation showing a photo printing and numbering apparatus constructed in accordance with the present invention, portions of the construction being broken away, and the dotted lines in said view illustrating the position assumed by the moving parts when thrown into inoperative position;

65 Figure 2 is a plan view of the same;

Figure 3 is an enlarged section taken on the line III—III of Figure 2; and

Figure 4 is a similar section taken on the line IV—IV of Figure 1.

Referring now to the drawings in detail, 70 these illustrate the improved apparatus as comprising a framework, such as a table 6 provided with supporting legs 7, within the top of which table is constructed a light chamber or compartment 8 having an incandescent light bulb 9 for printing purposes, the top of which light chamber or compartment 8 is provided with the usual transparent photo-printing surface such as is afforded by a glass plate 10 for supporting 80 a negative 11 and print paper 12 in superposed relation in the usual manner, as illustrated in Figures 3 and 4. The structure thus far described is common, and our improvements consist in the provision for enabling the print 12 to be marked centrally with an identifying number applied substantially centrally of the print at the same time as the photo print is produced.

The print paper 12 and negative 11 are 90 adapted to be pressed upon the printing surface provided by the glass plate 10 by means of a suitable light-excluding cover member 14 somewhat larger in area than said printing surface, and carried by means of a pair 100 of arms 15 fulcrumed upon pivot pins 16 carried in bracket lugs 17 formed as part of a bracket 18 secured to the top of the table 6 at one side of the light chamber 8. Spring members 19 are attached to the pivoted ends 105 of the arms 15 in such a manner as to lift these arms and the cover member 14 carried thereby into more or less elevated position about the axis of the pins 16.

Formed centrally in the cover member 110 14 is an opening 20 adapted to accommodate the lower portion of the framework

21 of a numbering machine of any desired commercial form, having the usual number changing lever 24. This machine is carried by a suitable frame piece 22 connecting the forward ends of a pair of arms 23, the rear ends of which are fulcrumed upon the inner ends of the pivot pins 16 as clearly illustrated in Figure 2, thereby adapting the numbering machine 21 to be 5 lifted about the same axis as the cover member 14. However, the opening 20 in the cover member is such as to provide sufficient clearance to accommodate a slight tilting movement of the cover member 14 10 with reference to the frame portion 21 of the numbering machine in response to the action of the spring elements 19 between successive photo printing operations, as hereinafter described.

20 The numbering device proper 25 has the usual reciprocatory movement within the framework 21 of the numbering machine, said device 25 being reciprocated by a plunger rod 26 retained normally elevated 25 by means of a coil spring 27, which rod 26 is in the present construction provided with a yoke member 28 secured to the upper end of the rod 26 and having at its opposite ends a pair of pins 29 for retaining 30 engagement with a pair of coil compression springs 30, the lower ends of which springs 30 are retained by means of a similar pair of pins 31 projecting up from the upper face of the cover member 14 at opposite 35 sides of the numbering machine 21. This spring construction is for the purpose of effecting engagement of the cover member 14 with the printing surface under a slight yielding pressure transmitted through the 40 springs 30 by the action of the operating means employed for depressing the plunger rod 26 in the numbering operation.

45 The operating means referred to comprises a foot lever or pedal 35 mounted in a floor bracket 36 and connected through a rod 37 with the rear end of a bell crank lever 38 fulcrumed to the upper end of an upright extension 39 from the bracket 18, the forward end of the lever 38 forming a 50 toggle connection with a link 40 having a turnbuckle 40'; said link 40 being in turn provided with a pivotal connection (as indicated at 41) with a plate 42 secured to the lower end of the plunger rod 26. The 55 toggle connection to the numbering device is adapted to be broken by raising of the rod 37, on depressing the front end of the pedal 35, as indicated by the broken lines in Figure 1, and vice-versa is adapted to be straightened in effecting the printing and numbering operation by the lowering of said rod 37 and depressing the rear end of said pedal 35 as shown in the full lines in Figure 1, the straightening movement of 60 the toggle being limited by means of a lug 65

45 formed on the front end of the bell crank lever 38 in position for limiting engagement with the rear end of the link 40.

70 In the operation of the apparatus, the negative and print paper are placed in appropriate position upon the transparent printing surface, that is, on top of the plate 10 over the light chamber or apartment 8, and the cover member 14 with its numbering machine lowered by rocking of the pedal 75 35 into the position represented by the full lines in Figure 1. In this operation, the arms 15 and 23 are swung about the same axis with the cover member 14 retained at a slight angle to the numbering machine 80 21, on account of the action of the springs 19, which serve to maintain the upper face of the cover member 14 engaged with the inclined lower face 46 of the frame piece 85 22, as shown in Figure 3. This allows the lower face of the numbering machine 21 to come first into engagement with the print paper 12, which may therefore be further 90 adjusted by the operator before the final operation of printing and numbering due to the straightening of the toggle connection. The final movement of the pedal 35 then straightens said toggle connection, thereby depressing the plunger rod 26 in 95 engagement with the print, and simultaneously rocking the cover member 14 also into lowered position in engagement with the print 12 with a yielding pressure due to the connections (formed by yoke 28 and 100 springs 30) between said plunger rod 26 and the upper face of the cover member 14. By means of the turnbuckle 40' the stroke of the numbering device can be suitably adjusted for obtaining the proper relative movement between said device and the 105 cover member 14.

110 It will thus be seen that we have provided a practical and efficient apparatus for carrying out the desired objects of the invention. The provision for a tilting movement of the cover member, as represented in Figure 3, allows the operator to obtain access to the parts beneath the cover and conveniently from the front of the machine 115 for positioning the negative and print paper and adjusting the position thereof as often as desired, without any unnecessarily wide range of movement of the cover member, and the yielding action with which the cover member is applied into photo-printing position obviates any danger of the operator's fingers becoming injured in case they should be caught beneath the cover member. Furthermore the marking of the prints with 120 the desired number substantially centrally upon the print is a feature of advantage, as compared with the usual marking operation upon the margin of the print where the number is often cut away in the trimming of the print.

While we have illustrated what we now deem to constitute the preferred form of construction for embodying the improvements, we wish to be understood as reserving the right to make such changes or modifications as may fairly fall within the scope of the appended claims.

What we claim is:

1. A photo printing apparatus comprising a framework having a light chamber provided with a transparent printing surface, a cover member movable into and out of cooperative relation to said printing surface, a numbering device associated with the central portion of said cover member and movable relatively thereto, means for actuating said numbering device into engagement with the photo print, a connection between said actuating means and said cover member operative to actuate said cover member yieldingly into photo printing position, and a projection formed on said numbering device for engaging and lifting said cover member into inclined position between successive printing operations.

2. A photo printing apparatus comprising a frame-work having a light chamber provided with a transparent printing surface, a cover member movable into and out of cooperative relation to said printing surface, said cover member having a central opening, and an independently supported numbering device operating through said opening to mark a number on the photo print, means for actuating said numbering device into engagement with the photo print, and means actuated by said first means for simultaneously moving said cover member into photo printing position.

3. A photo printing apparatus comprising a framework having a light chamber provided with a transparent printing surface, a cover member movable into and out of cooperative relation to said printing surface, said cover member having a central opening and a numbering device operating through said opening to mark a number on the photo print, said cover member and numbering device being provided with independent supporting arms mounted for swinging movement about the same axis, and means for simultaneously actuating said cover member and numbering device into photo printing and numbering position and adapted to move said cover member into inclined relation to said printing surface between successive printing operations.

4. A photo printing apparatus comprising a framework having a light chamber provided with a transparent printing surface, a cover member movable into and out of cooperative relation to said printing surface, said cover member having a central opening, and an independently supported numbering device operating through said opening to mark a number on the photo print, and operating mechanism including toggle links operative on straightening thereof to simultaneously actuate said cover member and numbering device into printing and numbering position, and means adapted on breaking of said toggle links to move said cover member into inclined relation to said printing surface.

In witness whereof we hereunto affix our signatures.

BENJAMIN F. MIKESELL.

HARRY F. GILLIAM.
